UNITED STATES PATENT OFFICE.

WILLIAM E. PATCHIN, OF ROCHESTER, NEW YORK, ASSIGNOR TO LILIAN B. HODGE,
OF ROCHESTER, NEW YORK.

EAVES-TROUGH HANGER.

1,020,951.

Specification of Letters Patent. Patented Mar. 19, 1912.

Application filed June 22, 1911. Serial No. 634,747.

To all whom it may concern:

Be it known that I, WILLIAM E. PATCHIN, a citizen of the United States, residing at Rochester, in the county of Monroe and State of New York, have invented certain new and useful Improvements in Eaves-Trough Hangers, of which the following is a specification.

The object of this invention is to produce 10 a cheap, strong and durable eaves trough hanger made of channeled material.

A further object of this invention is to provide a suitable connection between the curved channeled portion of the eaves trough 15 circle and the base or supporting plate therefor.

A further object of my invention is to provide suitable attachments on the circle for securing the trough or gutter thereto.

20 These and other objects of my invention will be illustrated in the drawings and fully described in the specification and pointed out in the claims at the end thereof.

In the accompanying drawings, Figure 1 25 is a side elevation of my improved eaves trough hanger. Fig. 2 is a rear elevation of the hanger illustrated in Fig. 1. Fig. 3 is a vertical section taken on the line 3^x—3^x of Fig. 2. Fig. 4 is a rear elevation of the 30 channeled supporting plate for the eaves trough hanger, being a modification of the supporting plate shown in Figs. 1, 2 and 3. Fig. 5 is a vertical cross section on the line 5^x—5^x in Fig. 4. Fig. 6 is a perspective view 35 of the channeled circle with a modified channel support therefor. Fig. 7 is a perspective view of the right hand end of the eaves trough circle shown in Fig. 6. Fig. 8 is a modification of the base plate with a 40 channel attached thereto and interposed between the base plate and the circle supported therefrom. Fig. 9 is a modification of the parts shown in Fig. 8. Fig. 10 is a side elevation of the special finger that may 45 be used in connection with my eaves trough hanger. Fig. 11 is a detail view of the blank out of which my improved circle may be formed.

In the accompanying drawings like reference numerals refer to like parts.

I provide a base plate 1 having screw holes 2, 2 therein, preferably at the corners thereof. At the top and bottom of this base plate I have cut out on two sides the sections 55 3 and 4, which sections are bent up

at right angles to the base plate 1, so as to form the lugs 5 and 6 thereon. I also provide a curved channel 7 which is made preferably of a single piece of sheet metal bent first to the form of a straight channel having the fingers 8 and 9 projecting from the ends thereof and integral therewith. This channel is afterward bent to the circular form illustrated in the several figures. This channel is of suitable width to embrace 60 within it the lugs 5 and 6, the base plate 1 and the channel 7 being fastened together by the rivet 10. The lugs 5 and 6 are of sufficient length to hold the circle away from the base plate, leaving a small interval there- 65 between, and the length of the lugs 5 and 6 may be varied to vary the angular pitch 70 of the circle on the base plate.

The base plate 1 may be formed as illustrated in Figs. 4 and 5, in which case a single sheet of metal 11 is bent to form a channel 12 therein extending thereacross, which channel can be engaged by the channeled circle 7. A vertical section through this channel is illustrated in Fig. 5. 80

Instead of the base plate 1 I may use a single elongated channel 13, which channel is illustrated in perspective in Figs. 6, 8 and 9. In Fig. 6 the channel 13 is perforated at suitable intervals as shown at 14, 14. The 85 top of it is bent back as shown in Fig. 6, or forward as shown in Fig. 9, for the purpose of conforming to the shape of the wall and the eaves of the building. A base plate similar to the base plate 1 may be used in 90 connection with the vertical channel 13, the lugs 5 and 6 being struck up therein and the base plate and the channel being fastened together by the rivet 15. With this type of mounting, the circle 16 may be slotted as 95 illustrated at 17, and the circle may be clamped to the channel 13 by means of a stove bolt. The bolt may be passed through any one of the holes 14, 14 in the channel and the slot 17 in the circle permits a vertical adjustment on the bolt so that any range of adjustment may be secured thereby. With the part 13 formed in the shape of a channel and the circle 16 formed in a channel as well and fitting to the channel 13, the 100 parts may be securely held together, preventing either lateral or vertical movement of the one on the other. The trough 18 that is supported by the hanger rests in the circle 7, and as illustrated in Fig. 1, the back edge 110

thereof is raw and the front edge thereof is finished with a roll edge. The fingers 8 and 9 in Fig. 6 on the channel circle can be bent down over the edges of the trough for the purpose of engaging with the trough and holding it securely in position on the circle. These fingers too permit of a considerable range of adjustment by which they can be accommodated to troughs of different size.

10 As illustrated in Fig. 1, the edge of the trough 18 extends up beyond the channeled portion of the circle and is bent inward, being illustrated by the line 19, and the finger 8 is bent around such extended portion of the trough, and for the purpose of engaging it and holding it in place is just as effective as though the trough were narrower. The finger 9 on engaging the other side of the trough is equally effective in this respect, being flexible and readily bent to conform to the shape of the finished edge of the trough, just as the finger 8 is flexible and can be bent to conform to the shape of the unfinished edge of the trough. It has been found in practice that these fingers 8 and 9 after repeated bendings may break off, and to avoid soldering or riveting on a fresh finger, I provide the following feature of construction in the circle. The channel 16 is perforated at 20 for the purpose of receiving therein a loose or adjustable finger 21. This finger consists of a plain strip of metal somewhat longer than the finger 9, having an offset 22 formed therein, which 35 offset engages with the slot 20 and by which it is securely held in place. This finger can be set in place and bent around the edge of the trough practically the same as though it were integral with the circle.

40 As illustrated in Fig. 1, the finger 9 may be purposely left short so as to be inserted between the main body portion of the trough and the rolled edge thereof. In Fig. 1 at the right hand side I have illustrated the 45 special finger 21 used to embrace the outside of the edge of the trough, while the finger 9 passes into the groove in the trough just back of the rolled edge. This finger 9 stiffens the outer edge of the trough and 50 holds it in place when any undue pressure is brought against it, such as might be caused by the resting of a ladder against the edge of the trough. In this way both the finger 9 which is integral with the curved channel, and the finger 21, which 55 is special and detachably attached thereto, may be used at the same time. The finger 9 may regularly be made long in the manufacture of the circle and when a short finger 60 is desirable instead of a long one, the excess length of the finger may be cut off, leaving the circle and its finger of the form shown in Fig. 1.

Having thus described my invention, what 65 I claim as new and patentable is as follows:

1. In an eaves trough hanger, the combination of a semi-circular support comprising a channel formed up of a single sheet of metal and having a flexible finger extending from the middle surface of the channel at each end of the circle. 70

2. In an eaves trough hanger, the combination of a semi-circular support formed of a single sheet of metal bent laterally to the form of a channel and bent longitudinally 75 to the form of a semi-circle, perforations through the sides thereof, a supporting plate therefor having a channel formed therein, perforations through the side of said channel, perforations through the semi-circular support being adapted to register with the perforations in the channel of said supporting plate.

3. In an eaves trough hanger, the combination of a semi-circular support formed of a single sheet of metal bent laterally to the form of a channel and bent longitudinally to the form of a semi-circle, elongated slots through the channeled sides thereof, a supporting plate therefor having a channel formed therein, perforations through the side of said channel, a bolt passing through the slots in the semi-circular support and the perforations in the supporting plate, permitting a limited longitudinal adjustment of said semi-circular support on said bolt and said supporting plate, said bolt serving to clamp the semi-circular support to the supporting plate. 90

4. In an eaves trough hanger, the combination of a semi-circular support comprising a channel formed up of a single sheet of metal and having a flexible finger extending from the middle surface of the channel at each end of the semi-circle, an eaves trough supported in said semi-circular support, said fingers being bent around and engaging with the edges of said eaves trough for the purpose of holding it in place. 100

5. In an eaves trough hanger, the combination of a semi-circular support comprising a channel formed up of a single sheet of metal, said channel having a slot extending across the middle side thereof near the end thereof, a finger composed of a single piece of flexible metal having an offset end passing through said slot and engaging therewith and bearing against both the inside and the outside of the semi-circular support. 110

6. In an eaves trough hanger, the combination of a semi-circular support comprising a channel formed up of a single sheet of metal, said channel having a perforation extending across the middle side thereof near the end thereof, a finger composed of a single piece of flexible metal having an offset end passing through said slot and engaging therewith and bearing against both the inside and the outside of the semi- 120

circular support, a trough supported in said semi-circular support, said finger being adapted to be bent over the edge of said trough and fastened to said semi-circular support.

- 5 7. An eaves trough semi-circular support made of a single sheet of metal bent to the form of a channel, said channel having three sides, a base for supporting said
- 10 semi-circular support, said base having projections thereon with which the three sides of said channel engage for the purpose of being supported and braced thereby, said projections filling said channel, means for
- 15 fastening said semi-circular support to said base plate.

8. In an eaves trough hanger, the combination of a channeled semi-circular support

having a finger projecting from the outer edge thereof, a slot extending across said channel adjacent to said finger, a special finger detachably engaged with said semi-circular support through said slot, an eaves trough supported by said semi-circular support, said eaves trough having a rolled edge, said first named finger being adapted to engage with said eaves trough back of said rolled edge, said detachable finger being adapted to engage with said eaves trough around the outside of said rolled edge. 30

In testimony whereof I affix my signature in presence of two witnesses.

WILLIAM E. PATCHIN.
